(57) **CLAIM**

The ornamental design for a USB flash memory device and carrier, as shown and described.

DESCRIPTION

FIG. 1 is a perspective view of a USB flash memory device and carrier in accordance with my new design.

FIG. 2 is an exploded perspective view thereof, wherein the USB flash memory device is shown separate and disengaged from its carrier.

FIG. 3 is a top view thereof.

FIG. 4 is a front view thereof.

FIG. 5 is a right side view thereof.

FIG. 6 is a left side view thereof; and,

FIG. 7 is a bottom view thereof.

The broken lines outlining electrical contacts and raised gripping surfaces in FIGS. 1-3 are for illustrative purposes only and form no part of the claimed design.

1 Claim, 4 Drawing Sheets

FIG. 1

FIG.2

FIG.4

FIG.3
